Fig. 6.

UNITED STATES PATENT OFFICE.

PATRICK H. READ, OF NEW PHILADELPHIA, OHIO.

AUTOMATIC SUITCASE-ALARM.

1,081,150.

Specification of Letters Patent.

Patented Dec. 9, 1913.

Application filed May 8, 1913. Serial No. 765,314.

To all whom it may concern:

Be it known that I, PATRICK H. READ, a citizen of the United States, residing at New Philadelphia, in the county of Tuscarawas and State of Ohio, have invented new and useful Improvements in Automatic Suitcase-Alarms, of which the following is a specification.

The invention relates to an alarm attachment for traveling bags, suit cases or the like, and more particularly to the class of automatic or electrically operated alarms therefor.

The primary object of the invention is the provision of an alarm of this character wherein an audible sound will be effected on the lifting of the bag, suit case or the like by a wrongful possessor so as to give a signal to bystanders that the bag, case or the like has been fraudulently or maliciously taken by a person other than the rightful owner thereof.

Another object of the invention is the provision of an alarm attachment of this character which can be easily and conveniently set for the sounding thereof on the lifting or carrying of the bag, grip or the like in the hands of an intruder, or the alarm can be locked so as to be sustained passive, thereby permitting the case, bag, grip or the like to be carried about by the owner without possibility of the accidental sounding of the signal.

A further object of the invention is the provision of an alarm attachment which is simple in construction, positive and reliable in operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings:—Figure 1 is a side elevation of a suit case showing the alarm attachment constructed in accordance with the invention applied. Fig. 2 is an edge elevation. Fig. 3 is a vertical longitudinal sectional view through the same. Fig. 4 is a sectional view on the line 4—4 of Fig. 1. Fig. 5 is a perspective view of the sliding plunger. Fig. 6 is a plan view looking toward the interior of the case with the base plate removed. Fig. 7 is a plan view of the

attachment with the casing partly broken away to show the relative relation of the cooperating parts. Fig. 8 is a view similar to Fig. 6, showing a modified form with the alarm attachment of the electro-mechanical type. Fig. 9 is a sectional view on the line 9—9 of Fig. 8.

Similar reference characters indicate corresponding parts throughout the several views in the drawings.

Referring to the drawings by numerals, 10 designates generally a suit case, and on which is mounted the alarm attachment presently described. The alarm attachment comprises an elongated substantially rectangular shaped casing 11 preferably constructed from metal, and is riveted or otherwise secured to the outer side of the suit case 10 at the point where the usual lock is mounted thereon. The usual lock 12 employed in suit cases in this instance is mounted in the casing 11 and is adapted to lock the cover or top of the suit case closed in the ordinary well-known manner. Suitably fixed to the top of the casing 11 are 70 bearings 13 in which are loosely engaged the out-turned pintle ends 14 of a swinging handle 15 which permits the suit case 10 to be carried in the hand when in use. The pintle ends 14 are concealed within socketed 75 housings 16 fixed to the outer face of the top of the casing so as to give a neat appearance to the suit case.

The top of the casing 11 is formed with an opening 17 contiguous to one of the pintle ends 14 of the handle 15 and over which extends a leaf spring 18 which is disposed longitudinally of the casing 11 and has one end riveted at 19 thereto while the opposite end is formed with an out-turned latch nib 20 movable into the path of travel of a locking tongue 21 integral with and projecting laterally from the out-turned end 22 of a movable plunger 23 disposed parallel with the spring 18 at one side thereof. Fixed to the inner face of the casing 11 adjacent to the spring 18 is a guide 24 in which works the plunger 23, the latter being formed with an in-turned tap rim 25 which also serves as a bearing for one end of a bowed leaf spring 26 which has its opposite end fixed to one side wall of the casing 11, the spring being designed to move the plunger 23 in one direction after its locking tongue 21 has been released from the latch nib 20 on the 100 105 110

leaf spring 18 whereby the tap arm 25 will act upon a sounding or signaling device presently described.

Mounted within the casing 11 near one end thereof is a spring-actuated bell 27 which is of any ordinary well-known construction and becomes active on operating a push button 28 projecting outwardly from the said bell 27 at one side thereof in the path of movement of the tap arm 25 which is adapted to act upon the button 28 for pushing it when the plunger 23 is automatically moved in one direction for the sounding of the bell. It is of course understood that the bell 27 is mounted within the casing 11 so as to depend within the suit case 10, the edge wall of the suit case being cut away to accommodate the said bell.

Mounted in the pintle ends 14 of the handle 15 adjacent to the plunger 23 is a cross trip pin 29 which on the swinging of the handle 15 to vertical position engages the spring 18 so as to move the same a distance whereby the nib 20 will disengage from the tongue 21 of the said plunger 23 and on the releasing of the nib 20 the cross trip pin 29 will lie in the path of the tongue 21 to hold the plunger 23 retracted until the handle 15 is swung in the reverse direction, which will move the pin 29 out of the path of the tongue 21 of the plunger and thereby freeing the latter so that under the action of the spring 26 its tap arm 25 will be forced against the push button 28 of the bell 27 for the sounding of the latter to give an audible signal.

Mounted exteriorly of the casing 11 at one side of the plunger 23 is an escutcheon plate 30 having journaled therein and in a bracket 31 fixed to the inner face of the casing a lock key receiving barrel 32 in which is adapted to be inserted a key (not shown) of the lock 12 so that the bit of the key when inserted in the barrel 32 will work in the path of and engage a lateral projection 33 on the plunger 23 when the said key is turned in one direction to retract the said plunger whereby its tongue 21 will engage with the nib 20 on the spring 18, thereby locking the plunger in retracted position and under the tension of the spring 26 so that on the swinging of the handle to vertical position the plunger will be free to move in a direction to bring its tap arm 25 against the push button 28 and force it inwardly for the sounding of the bell. It is of course to be understood that the key to be used is so constructed that it will operate the lock 12 as well as operating the setting of the plunger or retracting it in a manner as hereinbefore described.

Mounted on the inner face of the top of the casing 11 is a guide member 34 in which is slidably mounted a safety device which comprises a slide 35 disposed at right angles

to or transversely across the path of movement of the plunger 23, the slide being formed with a tooth 36 which is brought into alignment with the plunger 23 when retracted on moving the slide 35 so as to hold the said plunger against movement when swinging the handle to raised or lowered position, thereby preventing the ringing of the bell 27 and thus prevent the sounding of the alarm.

The slide 35 is formed at one end with a notch 37 providing opposed shoulders 38 and 39 respectively with either of which is adapted to engage the bit of the key when inserted in the barrel 32 so that the slide 35 can be moved in positions for locking or unlocking the plunger 23 to prevent it from contacting with the push button 28 or the bell 27 or to allow the plunger to move when released on actuating the handle 15 of the suit case 10 whereby the tap arm 25 will exert pressure upon the push button 28 for the sounding of the bell.

Fixed interiorly of the suit case 10 and enclosing the bell 27 is a housing 40, the same being formed with a central hole 41 through which projects a square lug 42 fixed to the turning section 43 of the said bell 28 and with this lug 42 is adapted to be engaged an ordinary clock key for the winding of the spring of the bell 27 when the same has become unwound, it being necessary to open the case for the winding of the spring of the bell 27. Presuming that the spring of the bell 27 has been wound for the automatic sounding of the latter and it is desired to set the alarm attachment after the suit case has been locked the key of the lock 12 is inserted in the barrel 32 and on the turning of the said key the plunger 23 is retracted whereby its tongue 21 will engage with the nib 20 of the spring 18. Now on the lowering of the handle 15 of the suit case 10 to one side the cross pin 29 will act upon the spring 18 causing the disengagement of the nib 20 thereof from the tongue 21 of the plunger 23 which will automatically move a limited distance until its tongue 21 engages the pin 29 carried by one pintle end 14 of the handle 15 so that on raising or moving the said handle 15 in the reverse direction the pin 29 will disengage from the tongue 21 freeing the plunger 23 which under the action of the spring 26 will be moved in a direction to bring its tap arm 25 against the button 28 of the bell 27 and the pressure of the tap arm 25 against the button 28 will effect the automatic ringing or sounding of the bell 27, thereby giving a signal that the suit case is being tampered with by a person other than the rightful owner thereof. Should it be desired to prevent the sounding of the bell 27 the key is inserted in the barrel 32 and turned in a direction to retract the plunger 23 which will be automatically

locked in this position by the latch nib 20, then on turning the key in the reverse direction it engages the shoulder 38 and the slide 35 will be moved to bring its tooth 36 in the path of movement of the plunger 23 and thus locking the latter against movement so that its tap arm 25 will not contact with and exert a pressure against the push button 28 of the bell 27 should the handle 15 of the suit case 10 be raised or lowered in either direction.

In Figs. 8 and 9 of the drawings there is shown a slight modification of the invention, wherein there is employed an electric dry battery 44 which is secured within the casing 45 of the alarm attachment, the casing being mounted in a manner as hereinbefore described, and connected with the poles 46 and 47 of the battery 44 are current wires 48 which are also connected with an electrically operated bell 49 arranged in the electric circuit, which includes a contact 50 disposed in the path of movement of a circuit closing arm 51 formed on one pintle end 52 of the handle 53 of the suit case 10, the electric circuit being normally open when the arm 51 is out of engagement with the contact 50, and on the movement of the handle 53 in one direction the arm 51 will engage the contact 50, thereby closing the electric circuit for the sounding of the bell 49 for signaling purposes as hereinbefore set forth.

It is of course to be understood that the contact 50 is insulated from the casing 45 and also that one of the current wires 48 is suitably connected with the arm 51 so that the circuit will be closed when the said arm engages with the contact 50, thereby causing the ringing of the electric bell 49 for signaling. The arm 51 is brought into engagement with the contact 50 when the handle 53 is raised from lowered position.

From the foregoing it is thought that the construction and manner of operation of the device will be clearly understood, and therefore a more extended explanation has been omitted.

What is claimed is:—

1. An alarm attachment comprising a casing adapted to be mounted on a traveling bag, a swinging handle connected with the casing, a sounding device fixed to the casing and depending within the traveling bag, a plunger movably connected with the casing interiorly thereof, a spring held latch member engageable with the plunger to hold the same retracted, a tap arm formed on the said plunger and adapted to actuate the sounding device, means for moving the plunger in operative relation to the said sounding device, and means operative by the handle for releasing the latch from the plunger and also freeing the latter whereby its tap arm will be brought into operative

relation to the sounding device for actuating the same.

2. An alarm attachment comprising a casing adapted to be mounted on a traveling bag, a swinging handle connected with the casing, a sounding device fixed to the casing and depending within the traveling bag, a plunger movably connected with the casing interiorly thereof, a spring held latch member engageable with the plunger to hold the same retracted, a tap arm formed on the said plunger and adapted to actuate the sounding device, means for moving the plunger in operative relation to the said sounding device, means operative by the handle for releasing the latch from the plunger and also freeing the latter whereby its tap arm will be brought into operative relation to the sounding device for actuating the same, and a key receiving barrel mounted upon the casing and adapted to receive a key for effecting the retracting of the plunger after operating the sounding device.

3. An alarm attachment comprising a casing adapted to be mounted on a traveling bag, a swinging handle connected with the casing, a sounding device fixed to the casing and depending within the traveling bag, a plunger movably connected with the casing interiorly thereof, a spring held latch member engageable with the plunger to hold the same retracted, a tap arm formed on the said plunger and adapted to actuate the sounding device, means for moving the plunger in operative relation to the said sounding device, means operative by the handle for releasing the latch from the plunger and also freeing the latter whereby its tap arm will be brought into operative relation to the sounding device for actuating the same, a key receiving barrel mounted upon the casing and adapted to receive a key for effecting the retracting of the plunger after operating the sounding device, and a safety device movable into the path of movement of the plunger and adapted to be operated by the key when inserted in the barrel on the turning of the said key in one direction.

4. An alarm attachment comprising a casing adapted to be mounted on a traveling bag, a swinging handle connected with the casing, a sounding device fixed to the casing and depending within the traveling bag, a plunger movably connected with the casing interiorly thereof, a spring held latch member engageable with the plunger to hold the same retracted, a tap arm formed on the said plunger and adapted to actuate the sounding device, means for moving the plunger in operative relation to the said sounding device, means operative by the handle for releasing the latch from the plunger and also freeing the latter whereby its tap arm will be brought into operative re-

lation to the sounding device for actuating the same, a key receiving barrel mounted upon the casing and adapted to receive a key for effecting the retracting of the plunger after operating the sounding device, a safety device movable into the path of movement of the plunger and adapted to be operated by the key when inserted in the barrel on the turning of the said key in one direction, and means on the casing for guiding the plunger in its movement.

5. An alarm attachment comprising a casing adapted to be mounted on a traveling bag, a swinging handle connected with the casing, a sounding device fixed to the casing and depending within the traveling bag, a plunger movably connected with the casing interiorly thereof, a spring held latch member engageable with the plunger to hold the same retracted, a tap arm formed on the said plunger and adapted to actuate the sounding device, means for moving the plunger in operative relation to the said

25 sounding device, means operative by the handle for releasing the latch from the plunger and also freeing the latter whereby its tap arm will be brought into operative relation to the sounding device for actuating the same, a key receiving barrel mounted upon the casing and adapted to receive a 30 key for effecting the retracting of the plunger after operating the sounding device, a safety device movable into the path of movement of the plunger and adapted to be operated by the key when inserted within the 35 barrel on the turning of the said key in one direction, means on the casing for guiding the plunger in its movement, and means on the casing for guiding the safety device in its movement.

40 In testimony whereof I affix my signature in presence of two witnesses.
